Primary Examiner—Philip S Hyder*Assistant Examiner*—Roselynne Cody(74) *Attorney, Agent, or Firm*—Luedeka, Neely & Graham, P.C.(57) **CLAIM**

The ornamental design for an under-bed security cabinet, as shown and described.

DESCRIPTION

FIG. 1 is a top perspective view of the under-bed security cabinet;

FIG. 2 is first end view of the under-bed security cabinet;

FIG. 3 is a second end view of the under-bed security cabinet;

FIG. 4 is a side view of the under-bed security cabinet;

FIG. 5 is a top plan view of the under-bed security cabinet; and,

FIG. 6 is a bottom plan view of the under-bed security cabinet.

The broken lines in FIG. 6 illustrate environment and form no part of the claimed design.
